United States Patent Office

Des. 194,644
Patented Feb. 19, 1963

194,644

PORTABLE WATER COOLER, OR SIMILAR ARTICLE

Fred Jacobs, Plainview, N.Y., assignor to Air-X Industries, Inc., Bronx, N.Y., a corporation of New York

Filed July 30, 1962, Ser. No. 71,108

Term of patent 14 years

(Cl. D67—3)

FIG. 1 is a front perspective view of a portable water cooler, or similar article, showing my new design; and FIG. 2 is a rear perspective view thereof.

I claim:

The ornamental design for a portable water cooler, or similar article, substantially as shown.
